UNITED STATES PATENT OFFICE.

STEPHEN D. FRY, OF ATTICA, INDIANA.

FENCE-MAKING MACHINE.

SPECIFICATION forming part of Letters Patent No. 326,029, dated September 8, 1885.

Application filed June 4, 1885. (No model.)

To all whom it may concern:

Be it known that I, STEPHEN D. FRY, a citizen of the United States, residing at Attica, in the county of Fountain and State of Indiana, have invented certain new and useful Improvements in Fence-Weaving Machines, of which the following is a specification, reference being had therein to the accompanying drawings.

10 My invention relates to improvements in fence-making machines, and is designed to produce a device wherein the fence is made of pickets connected by wire.

The improvement consists, essentially, in the mechanism whereby the wire is given the necessary alternate twist and also the necessary tension; also in the picket-clamp, whereby it is held while the twisting operation is in progress, and the spacing mechanism.

15 In describing the device reference is had to the annexed drawings, in which Figure 1 represents a plan view of the device; Fig. 2, a side elevation partly broken away, and Fig. 3 an end elevation with parts broken away; Fig. 20 4, a detail perspective of one end of the reel with the parts separated.

On upright standards A are supported cross-pieces B, a space being left between them. In circular openings in the cross-pieces B rest the 30 ends of the twisting-heads C, each having passages entirely through them for the wire, and having cog-teeth of the width of the space between the pieces B.

To one side of each twisting-head C are vertically-moving rack-bars D, intermeshing with the rack or cog teeth on the said twisting-heads C, and joined by strips E at the top and bottom, so as to move simultaneously. On the bars D is also a series of rack-teeth coincident 40 with and at right angles to those engaging with the twisting-heads C.

Journalized in the uprights A, below the pieces D, is a shaft, F, having pinions intermeshing with the rack-bars and operating them to impart the alternate rotation to the twisting-heads C. The shaft has a crank, by means of which it is operated.

On one end of the machine is a frame carrying a series of spools, G, holding the wire. 50 These spools are arranged in pairs, and have their spindles (those of each pair) connected by a strip, H. Centrally on this strip is raised

a vertically-adjustable post, I, on which is a spring-clamp, K, the ends of which rest on the ends of the strip H. The spring K, as it is drawn toward the strip H by the bolt I, will tend to lift the central portion of the said strip H and depress the ends thereof, thus forcing the said ends against the top of the spools and retarding their motion to a greater or less extent.

At the end of the machine opposite to that occupied by the spools is the reel L, which is formed of two strips, clamping, by means of bolts L', the spindles M, one of which extends 65 beyond the frame-work and carries a ratchet-wheel, N, and also a pawl-lever, O, the end of which rests normally in the bracket P. The finished fence is wound on the reel as fast as made, and when full said reel is removed by 70 unscrewing the bolts. The removal of the spindles allows the approach of the two strips, and as the fence is rigid they may be readily removed and replaced in the machine.

On the same side of the twisting-heads C as 75 is the reel is a rock-shaft, R, having an arm, S, at one end, connected by a link or rod, N', to a treadle, T, by means of which it is operated. This shaft has centrally an arm, U, which operates to raise the hinged lower jaw 80 of a clamp, V, projecting from the side of the pieces B. Within this clamp is placed each paling or picket in turn, it passing between the wires, and being firmly there held while the wires are given a twist, thus securing it in 85 its place. Brackets W on the ends of strips X, which pass through slots in the pieces B, push the paling forward as the clamp is loosened, and another paling is inserted. The strips X are joined at the rear ends, and are 90 normally held away from the paling by a spring, Y.

A strap, Z, passes from the connecting-piece around the shaft F to a treadle, A', which, when depressed, causes the strips, with their 95 brackets or heads, to advance.

On the strips or pieces B is journalized a rock-shaft, B', to a projecting arm on which is connected by a link or rod, M', the treadle A'.

Projecting from the shaft toward the end of 100 the machine containing the reel are slotted arms C', carrying adjustably, by means of clamp-nuts, the connected angle-arms D', slotted coincidently with the arms C'. By means

of the adjustment the arms may be lengthened or shortened at pleasure.

When the newly-fastened paling is pushed forward, the treadle raises the arms C' D', which as soon as the treadle is released fall again into place by the force exerted by the springs Y through the strip X and strap Z, thus raising the treadle A' and causing the said arms to fall either from gravity or because of the inflexible connection. The slack of the fence is then taken up by the reel until the paling rests against the arms D', the distance of which from the clamp V regulates the distance between the palings.

15 I claim—

1. In a fence-making machine, a twisting device consisting of twisting-heads with wire-passages through them and cog-teeth on them, rack-bars, one for each drum, having teeth on two surfaces, one at right angles to the other, and an operating-shaft with pinions engaging with the bars, substantially as and for the purpose specified.

2. In a fence-making machine, a device for holding the palings, consisting of a fixed jaw, 25 a pivoted jaw under the same, a rock-shaft operated by a treadle, and an arm on said shaft engaging under said movable jaw and operating to lift it toward the said fixed jaw, substantially as and for the purpose specified. 30

3. The combination, with the frame holding the twisting-heads, of brackets projecting through said frame and normally spring-retained, a treadle connected to said brackets by a strap, a rock-shaft on the frame, having 35 an arm connected to the treadle by a link or rod, and slotted arms projecting from said shaft and carrying adjustable angle-arms, substantially as and for the purpose specified.

In testimony whereof I affix my signature in 40 presence of two witnesses.

STEPHEN D. FRY.
